Russell C. Petersen(57) CLAIM

The ornamental design for a bottle, as shown and described.

DESCRIPTION

FIG. 1 is a front perspective view of the bottle showing my new design;

FIG. 2 is a front view of the bottle;

FIG. 3 is a rear view of the bottle;

FIG. 4 is a left side view of the bottle;

FIG. 5 is a right side view of the bottle

FIG. 6 is a top view of the bottle; and,

FIG. 7 is a bottom view of the bottle.

The broken lines are shown for the purpose of illustrating parts of the bottle that form no part of the claimed design.
